UNITED STATES PATENT OFFICE.

STANLEY ROBERT WRIGHT, OF RAWDON, NEAR LEEDS, ENGLAND, ASSIGNOR TO
IGRANIC ELECTRIC COMPANY LIMITED, OF LONDON, ENGLAND, A CORPORATION
OF GREAT BRITAIN.

VARIABLE RECIPROCATING TRAVERSE MECHANISM.

Application filed August 22, 1921. Serial No. 484,410.

(GRANTED UNDER THE PROVISIONS OF THE ACT OF MARCH 3, 1921, 41 STAT. L., 1313.)

To all whom it may concern:

Be it known that I, STANLEY ROBERT WRIGHT, a subject of the King of Great Britain, and resident of Rawdon, near Leeds, Yorkshire, England, have invented certain new and useful Improvements in and Connected with Variable Reciprocating Traverse Mechanism (for which I have obtained a patent in Great Britain dated

10 May 29, 1919, No. 149,104), of which the following is a specification.

This invention relates to that type of reciprocating traverse mechanism for coil winding machines in which the wire or thread guide is reciprocated across the face of the spool by means of a continuous band driven unidirectionally. One object of the invention is to provide improved means in a mechanism of the above type for operatively connecting the wire or thread guide to such a band.

Another object is to provide means for automatically varying the shape of the coil according to varying requirements.

25 Other objects and advantages will appear hereinafter.

In order that the invention may be clearly understood the same will now be described by aid of the accompanying drawings in 30 which:

Fig. 1 is a plan view of part of a coil winding machine to which this invention is applied.

Fig. 2 is a side partly sectional elevation 35 of the same.

Fig. 3 is an end view of Fig. 2.

Fig. 4 is a section of a magnetic pulley used in connection with the invention in the present example of the same.

40 Fig. 5 is a diagram of the electrical connection of the apparatus.

According to the practical application of the invention shown in the drawings and as applied to a coil winding machine for reciprocating the wire or cotton traverse guide, the constant speed single direction motion is obtained from a motor not shown and is imparted to one of the band carrying pulleys *a* through the medium of bevel gears *c*, which, in the present application, 45 replace the usual cam.

To obviate slipping of the band under the

drive, a steel band *d* is used and the above-mentioned pulley *a* provided interiorly with a magnet *e* see Fig. 4, by means of which 55 the surface of the steel band in contact with the face of the pulley is attracted to such pulley face upon energization of the magnet. The other end of the endless band is held in variable spaced relation with the magnetic pulley by tie-rods *f* which is 60 also serve as slides or guide bars for the magnet carrying member *g*.

This member, in the present example, carries a pair of magnets *h* and *i* connected in series the poles *j* of which are in vertical alignment with each other, the outer faces *j'* of such each approaching to within a small distance of the inside faces of the 70 top and bottom runs respectively of the steel band *d*. In conjunction with each magnet pole is a pivoted armature *k* each of which is disposed with the respective run of the steel band interposed between such 75 armature and its pole. Upon alternate energization of the magnets the respective runs of the steel band are correspondingly attracted thereto and augmentation of this grip is obtained by the subsequent attraction of the respective armatures with the result that the magnet carrying member is reciprocated upon its guide bars.

Two links *k'* pivotally connected at their ends to opposite lugs *k''* respectively projecting from the hinge members to which the armatures *k* are rigidly attached, are provided for ensuring that the upper armature *k* shall be lifted clear of the endless band *d* when the lower armature *k* is attracted to its corresponding magnet.

Alternate energization of the magnets is effected by means of a pair of contacts *l* see Figs. 1 and 3, which are mounted in adjustable connection with a fixed rod or rods *m* which are insulated for the purpose so as to reside one upon each side of the magnet carrying member *g*. These adjustable contacts are caused to alternately be engaged by corresponding faces *n* on a contact secured to—in the present example—the wire guide *o* of the coil winding machine.

This wire guide is pivotally connected to the magnet carrying member as at *p* so as

to move therewith and in a plane at right angles to the axis of the coil to be wound. In operation the engagement between one face of the fixed contact and the corresponding adjustable contact results in the short-circuiting of one of the magnets and full energization of the other with the result that the armature of the energized magnet is closed and forms a gripping connection with the corresponding run of the steel band and consequent like movement of the magnet carrying member.

Upon traversing the full distance allowed by the other adjustable contact the process is repeated with a consequent reversal of motion.

The electrical connections between the contacts and magnets will be seen from Fig. 5 are such that whilst traversing the space intermediate the two adjustable contacts the two magnets are placed in series with one another. The resulting flux is sufficient to simultaneously operate the other whilst the current is cut down to enable the coils to re- main cool.

As indicated in dotted lines in the drawing, the pivoted wire guide *o* rests against the periphery of the coil being wound, therefore as the diameter of the coil increases, the pivoted wire guide is caused to correspondingly turn about its pivot. This results in the faces of the fixed contact engaging progressively different points of the adjustable contact surfaces. This feature is utilized to automatically obtain variations in the shape of the wound coil, such shape being a replica of the shape defined by the opposing edges of the adjustable contacts, which edges also control the length of traverse of the magnet carrying member and, as a consequence, the length of traverse of the wire guide. Thus in the embodiment illustrated, as the coil grows the wire guide will be turned about the pivot *p* in a counter clockwise direction (according to Fig. 3) and the contacts *n* will engage with the contacts *l* for effecting reversal of the wire guide, after strokes of progressively diminishing amplitude. The length of traverse will accordingly diminish with the result that a coil with beveled ends will be produced.

Had the contacting surfaces of the contacts *l* been at right angles to the stroke of the wire guide, it is obvious that a straight ended coil would have been produced.

What I claim and desire to secure by Letters-Patent is:—

1. A traverse mechanism for coil winding machines, comprising a reciprocable guide for the material to be wound, electro-magnetic means associated with said guide and movable therewith, an endless belt, of magnetic material adapted to be driven uni-

directionally, and means for energizing said electro-magnetic means so as to set up alternate magnetic attractions between certain of the poles thereof and portions of said endless belt adapted to travel in reverse sense.

2. A traverse mechanism for coil winding machines, comprising a reciprocable guide for the material to be wound, two electro-magnets connected to said guide and movable therewith, armatures for said electro-magnets, an endless belt of magnetic material adapted to be driven unidirectionally and so arranged that portions of its length which travel in reverse senses pass respectively between each electromagnet and its armature, and means for alternately energizing said electromagnets so as to cause them to attract each its armature and the portion of the belt passing between the magnet and its armature.

3. A traverse mechanism for coil winding machines comprising a reciprocable guide for the material to be wound, two electro-magnets in line with one another and rigidly connected to said guide, armatures for the remote poles of the electromagnets respectively, said armatures being connected together whereby attraction of one armature to its respective pole effects movement of the other armature from its respective pole, an endless belt of magnetic material adapted to be driven unidirectionally and so arranged that portions of its length which travel in reverse senses pass respectively between each electromagnet and its armature and means for alternately energizing said electromagnets so as to cause them to attract each its armature and the portion of the belt passing between itself and its armature.

4. A traverse mechanism for coil winding machines, comprising a reciprocable guide for the material to be wound, two electro-magnets connected to said guide and movable therewith, an armature for each electromagnet, an endless belt of magnetic material adapted to be driven unidirectionally and so arranged that portions of its length which travel in reverse senses pass respectively between each electromagnet and its armature, means whereby the windings of said electromagnets are normally both energized, and means for momentarily short circuiting said windings alternately each time the guide reaches the end of its stroke whereby said electromagnets are adapted to alternately attract and hold each its armature and the portion of the belt passing between itself and its armature.

5. A traverse mechanism for coil winding machines, comprising a guide for the material to be wound, means for effecting reciprocation of said guide longitudinally of the coil, electrical contacts adapted to engage

with one another for controlling the operation of said means, certain of said contacts being movable in accordance with the movement of said guide to engage with other of said contacts and thereby cause said means to effect reversal of said guide at each end of its stroke, and further means for causing the point of engagement of said contacts

with another to vary in accordance with the amount of material wound, whereby variations in the surface contour of certain of said contacts will cause corresponding variations in the shape of the coil. 10

In witness whereof I affix my signature.

STANLEY ROBERT WRIGHT.
